ASH RECEIVER

Charles Hardy, New York, N. Y.

Application August 1, 1935, Serial No. 34,159

4 Claims. (Cl. 131—51)

The present invention relates to an ash receiver, and more particularly to the type having an open hopper for receiving deposited butts and ashes, an ash and butt receiving and holding receptacle communicating with the hopper and a manually controllable closure for normally keeping the receptacle closed and for controlling the communication between the hopper and the receptacle.

10 The prime objects of the present invention center about the provision of an ash receiver of this type which may be conveniently and efficiently used by the smoker, which may be readily handled for cleansing purposes and which is capable of being manufactured and assembled to produce attractive smoking stands.

To accomplish these objects, the present invention has for its more specific purposes the provision of an ash receiver of the type referred to in which the hopper forms a fixed part of the ash receiver, the receptacle being a removable receptacle adapted to be lifted through the hopper bottom when it is desired to discharge or dump the contents of the receptacle; the further provision of an ash receiver of this type wherein the receptacle, normally hidden from view, is made readily accessible for facile removal from the ash stand upon a quick and ready detachment of the closure element; the further provision of an ash receiver of this construction wherein a bridge member is provided for movably supporting the closure element and which bridge member is formed to provide means for holding cigars or cigarettes; the still further provision of an ash receiver of this type wherein the closure element is movably mounted in a way to provide a self-seating adjustment when moved to its closed position so that a close fitting seating engagement of the closure element may be obtained; and the still further provision of an ash receiver embodying the construction referred to wherein all the parts are assembled for ready operation by the smoker, for quick and efficient cleansing by the housewife and for producing a distinctive and attractive appearance.

To the accomplishment of the foregoing and such other objects which may hereinafter appear, the invention consists in the ash receiver, preferably assembled as a smoking stand, and in the elements and combinations thereof as set forth in the appended claims and as exemplified in the drawing attached hereto in which:

Fig. 1 is a vertical perspective view of the assembled ash receiver of my present invention;

Fig. 2 is an enlarged view of the main and

upper part thereof taken in cross-section in the vertical plane of the line 2—2 in Fig. 1;

Fig. 3 is a top plan view thereof with the bridge member and closure element detached;

Fig. 4 is a bottom plan view of the said detached bridge member and closure element; and

Fig. 5 is a fragmentary view of detail taken in the plane of the line 5—5 in Fig. 3.

Referring now more in detail to the drawing, the ash receiver, when constructed in the form 10 of a smoker's stand, comprises a base member 10, an upright member 11 and a top hopper 12, all united together to form a stand of fixed parts. The said upright member is provided with or defines at its upper end a compartment 13 communicating at its open top with the open bottom 15 of the hopper 12. Seated in said compartment 13 is the removable ash receiving receptacle 14, which receptacle may be readily lifted from the compartment upon removal or detachment of a closure element 15 carried by a detachable bridge member 16, the closure element being movably mounted on the bridge member, and being movable thereon between the full and dotted line positions shown in Fig. 2 of the drawing. The full 20 line position shows the closure element in its normal condition for closing the receptacle 14 and for closing the communication between the hopper 12 and receptacle 14, and the dotted line position shows the condition assumed by the 25 closure element when the same is manually lifted to permit the ashes and butts deposited in the hopper to drop into the receptacle 14.

The ash stand may be conveniently constructed of sheet metal stock formed in sections capable of being readily assembled and united together to form a fixed unit. The base 10 made of sheet metal may be suitably weighted by a metal casting (not shown) located within the base, and the upright 11 may be made of a plurality of separate sections 11^a, 11^b, 11^c and 11^d nested together and held together as a unit by means of a rod 17 secured at its lower end to the metal casting of the base (not shown) and at its upper end to a threaded plate 18, which plate 35 fits in the bottom of a cup-shaped element 19 the top of which is seated over the flanged joint 20 of the upright section 11^d. The cup 19 serves as a bottom for the upright compartment 13. The hopper 12 is provided with an open bottom 12^a, 40 the edge wall of which is seamed to the edge wall 11^e of the upright 11 defining the open top 45 of the compartment 13. For decorative purposes the hopper may be provided with a marginal fluted skirt 12^b over the top of which the outer 50

marginal edge 12^c of the hopper is securely rolled or turned. All of these parts form a fixed unit, and may be decorated in different colors to produce a multi-tone effect.

5 The closure element 15 preferably comprises an upwardly convexed member having a rolled marginal edge 15^a adapted to efficiently fit in an annular groove or hollow 12^d formed near the open bottom of the hopper 12. The closure element 10 15 is mounted for up and down movement on a stem 15^b, surmounted by a preferably ball-shaped handle 15^c; and for the purpose of providing an efficient and vapor leakproof fit for the closure element 16, the said closure element is mounted 15 at the bottom of the stem in a manner to permit a limited vertical and limited free tilting movement in all directions of the closure element relatively to the stem. This latter is accomplished by loosely mounting the hub 15^d of the closure 20 element 15 on the stem at its bottom end and so that the closure element is freely movable on the stem between an upper flange 15^e and a lower washer 15^f on said stem.

The closure element 15 is movably supported 25 in the bridge member 16, the said bridge member being provided for this purpose with a vertically arranged guide bearing 16^a fitted to the center of the bridge member, which guide bearing 30 slidably receives the closure element stem 15^b. The bridge member 16 is desirably mounted on 35 the hopper 12 by means which permits the mounting or detaching of the bridge member by a simple displacement thereof relatively to the hopper. This means preferably comprises a pin and slot connection between the bridge member and the hopper, the bridge member being provided at its opposite ends for this purpose with the headed pins 16^b which mate with slots 12^e provided at diametric points on the top 40 face 12^f of the hopper 12. The bridge member 16 is also further provided with means for holding cigarettes or cigars in a way to permit the 45 depositing of falling ashes into the hopper 12, and preferably this is effected by forming the said bridge member with the cigarette receiving channels 16^c, 16^d and the openings 16^a, 16^b.

With this recited construction it will be seen 50 that the bridge member 16 together with the closure element 15 may be readily mounted in position on the fixed hopper 12 and may be fixed in position by merely imparting a slight turning displacement to the bridge member, the bridge member being anchored in its position by the pin and slot engagement. The closure element 55 15, by virtue of its mounting on the stem 15^b permitting a limited free tilting movement of the closure element in all directions, will readily adjust itself into close seating engagement for effectively closing the compartment 13 and the 60 receptacle 14 against exit of obnoxious fumes and vapors and for closing the communication between the same and the hopper 12. When it is desired to drop ashes or butts collecting in the 65 hopper into the compartment 13 or receptacle 14, the handle 15^e of the closure element is lifted and then the closure element is permitted gravitationally to return to its closed position. The closure element will again adjust itself into efficient seat closing condition. When it is desired 70 to discharge or dump the accumulated contents of the receptacle 14, the closure element is detached by giving to the bridge member a slight displacing movement in a counter-clockwise turning direction, which displacement will free 75 the bridge member for quick detachment thereof

and the closure element. The removable receptacle 14, normally concealed from view, will then be exposed to view and may be lifted from the compartment 13 and the contents of the receptacle discharged. For convenience, the receptacle 14 is provided at its upper end with a wire or rod shaped handle 14^a which obviously may be conveniently grasped by the user.

It will be further apparent that by means of the construction described, an assembly of parts 10 is provided which is subject to simple manufacturing operations and ready assembly and disassembly by the manufacturer and the user. In fact, all of the parts may be quickly taken apart or put together by a quick displacement of the 15 bridge member 16 and by removing the nut which is secured to the bottom of the anchoring rod 17. The parts are furthermore so organized as to provide an ornamental unit.

It will be apparent that while I have shown 20 and described my invention in preferred form, many changes and modifications may be made in the structure disclosed without departing from the spirit of the invention, defined in the following claims.

I claim:

1. An ash receiver comprising a base, an upright and a top hopper all united together to form a stand of fixed parts, the top of said upright defining a compartment directly communicating with the open bottom of said hopper, a separate ash receiving receptacle seated in said compartment and adapted to be lifted through the opening of said hopper for dumping the ash contents accumulating in said receptacle, a closure element normally closing the communication and manually movable upwardly to open the communication between the hopper and the said compartment, and mounting means for said closure element bridging the top of said stand, 30 the said mounting means and movable closure element being constructed and arranged relatively to said fixed hopper and communicating compartment to permit the said lifting of the separate ash receiving receptacle through the 35 opening of said hopper for the dumping of its contents.

2. An ash receiver comprising a base, a hollow upright made of sheet metal and a top hopper made of sheet metal all united together to form 50 a stand of fixed parts, the top of said upright defining a compartment communicating directly with the bottom of said hopper, a separate ash receiving receptacle seated in said compartment and adapted to be lifted through the opening of 55 said hopper for dumping the ash contents accumulating in said receptacle, a gravitationally controlled closure element normally closing the communication and manually movable upwardly to open the communication between the hopper 60 and the said compartment, a bridge member detachably mounted across the top of said hopper and being detachable from or mountable on the hopper by a displacement of the bridge member relatively to the hopper, and means for slidably mounting the closure element on the bridge member.

3. An ash receiver comprising a fixed ash receiving hopper having an open bottom, a movable ash receiving receptacle having an open top 70 communicating with the open bottom of the hopper, the said receptacle being adapted to be lifted through the opening of said hopper for dumping the ash contents accumulating in said receptacle, a movable closure element normally clos- 75

ing the communication between the hopper and the receptacle and movable upwardly to open such communication, and mounting means for said closure element consisting of a detachable bridge member normally bridging said fixed hopper and quickly detachable therefrom, said closure element being slidably and gravitationally mounted on said bridge member.

4. An ash receiver comprising a fixed ash receiving hopper having an open bottom, a body joined to said hopper at its open bottom, said body defining an open top compartment, a movable ash receiving receptacle in said compartment having an open top communicating with the open bottom of the hopper, the said recepta-

cle being adapted to be lifted from said compartment through the opening of said hopper for dumping the ash contents accumulating in said receptacle, a movable closure element normally closing the communication between the hopper and the receptacle and movable upwardly to open such communication, and mounting means for said closure element bridging said fixed hopper, the said mounting means and movable closure element being constructed and arranged relatively to said fixed hopper and communicating compartment to permit the said lifting of the separate ash receiving receptacle through the opening of said hopper for the dumping of its contents.
